UNITED STATES PATENT OFFICE.

SIGMUD W. ZIEMBINSKI, OF NEW YORK, N. Y.

BROOM AND MOP HANGER.

Application filed October 6, 1926. Serial No. 139,787.

This invention relates to improvements in hangers for brooms, mops and articles of a similar nature and has for one of its important objects the provision of a hanger 5 adapted to be secured to a wall or the like and to clampingly sustain either brooms, mops or the like having handles of various diameters or thicknesses.

Another important object of the invention 10 is to provide a hanger of this nature, simple and positive in operation and inexpensive yet substantial in construction.

Other important objects and novel features in construction of my invention will 15 become apparent as the specification proceeds.

Referring to the drawings forming a part 20 of this specification;

Figure 1 is a view in perspective of one 25 embodiment of my invention.

Figure 2 is a sectional view taken on line 2—2, Fig. 1 and

Figure 3 is a sectional view taken on line 3—3, Fig. 2.

Referring to the drawings in detail, 5 indicates a casing provided with an extending flange or base 6 having ears 7 at its upper and lower ends provided with holes or openings 8 through which screws 9 may be inserted to secure same to a wall 10 of a room or closet. A bar 11 having reduced ends 12 fitting into openings 13 in the top and bottom walls 14 and 15 of the casing 5, is angularly maintained on the inside of the said casing by the aforementioned connections and by a strip 16 secured by screws 17 to the lower portion of the flange 6 depending from the wall 15. A bracket 20 having a slideway 21 in its base 22 is slidingly mounted on the inclined bar 11 and is provided with a forwardly extending arm 23 extending through a vertical slot or opening 24 substantially the entire length of the front wall 25 of the casing 5 and terminates in an arm 26 bent at right angles to the arm 23 and is provided with a tapering recess 27 adapted to maintain therein a gripping pad 28 made of any suitable material such as rubber or the like.

With a device as described above it becomes a simple matter to suspend a broom, mop or the like and prevent such articles from resting on the floor, and allowing such articles and mops in particular to dry and be kept in a clean and sanitary condition and preventing such mops from soiling the floor as was heretofore the case when no such suspension means was provided.

From the foregoing it will be seen that my device is simple and efficient in operation and that all that is necessary to do, to suspend a mop or the like by means of my improved device, is to insert the handle 30 of such a mop upwardly through the bottom of the device between the front wall 25 of the casing and the rubber gripping pad 28 and the bracket or slide 20 will move upwardly until the handle fits into the space between the said wall and pad and the mop or other similar article will be positively supported therein by its own weight drawing the slide downwardly on the inclined bar 11. A slight upward pressure on the handle 30 will release same and allow of its being removed from the hanger. Various modifications and changes may be made in the arrangement and construction of the various parts of this device without departing from the scope of the appended claims.

Having described my invention what I claim as new is:

1. A hanger, comprising a casing, having a slot in one wall thereof, a bar angularly supported in the said casing, a bracket slidably mounted on the bar and a bent arm on the bracket extending through the said slot forming a space between itself and the said wall to frictionally hold a handle or the like.

2. A hanger, comprising a casing having a slot in one wall thereof, a bar angularly supported in the said casing, a bracket slidably mounted on the bar, a bent arm on the bracket extending through the said slot forming a space between itself and the said wall to frictionally hold a handle or the like and a pad on the arm forming means for gripping the handle.

SIGMUD W. ZIEMBINSKI.
